DESIGN FOR A MOTION PICTURE PROJECTOR BRACKET

Fred J. Wenzel, Chicago, Ill.

Application August 6, 1938, Serial No. 79,151

Term of patent 14 years

To all whom it may concern:

Be it known that I, Fred J. Wenzel, a citizen of the United States of America and a resident of Chicago, in the county of Cook and State of Illinois, have invented a new, original, and ornamental Design for a Motion Picture Projector Bracket, of which the following is a specification, reference being had to the accompanying drawing, forming a part thereof, and in which:

Fig. 1 is a perspective view of a motion picture bracket embodying my new design;

Fig. 2 is a rear elevational view of the same;

Fig. 3 is an end elevational view of the same as seen from the right hand end as seen in Fig. 1 or as seen from the left hand end as seen in Fig. 2; and

Fig. 4 is an end elevational view thereof as seen from the left hand end in Fig. 1 or as seen from the right hand end in Fig. 2.

I claim:

The ornamental design for a motion picture projector bracket, as shown.

FRED J. WENZEL.
